UNITED STATES PATENT OFFICE.

WALTER H. PFLUGER, OF NEW YORK, N. Y.

RAILWAY RAIL.

Application filed November 11, 1927. Serial No. 232,536.

As is well known, rails wear where the treads of wheels pass over them and also where the flanges of wheels engage them and that rails are worn out when good in all other parts.

The object of my invention is to provide a rigid rail with an easily replaced tread and this rail is simple in construction, durable in operation and easy to manufacture.

10 This and other objects are accomplished by my invention, one embodiment of which is hereinafter more particularly set forth.

For a more detailed description of my invention, reference is to be had to the accompanying drawings, forming a part hereof, in which:

Figure 1 shows a track provided with my improved rail.

Figure 2 shows a cross section of my improved rail.

Figure 3 is a plan view with parts broken away to more clearly reveal the structure.

Throughout the various views of the drawings, similar reference characters designate similar parts.

My improved rail 1 is placed on cross ties 2, in the conventional manner. This rail has a tread 3, clamping plates 4 and a base 5 which has upright flanges 6 and laterally extending webs 7 which are adapted to rest on cross ties 2, in the conventional manner. The clamps 4 and base 5 are held by suitable clamping bolts 8 which are provided with suitable washers 9 so that the parts may be firmly clamped together.

The tread 3 of the rail is given any desired shape on its top and on its lower surface is inclined inwardly and downwardly to a center projection 10 which is enlarged to 40 enter corresponding grooves in the clamps 4 and to prevent creeping, from time to time at desired intervals, the projecting part 10 is provided with laterally extending lugs 11, which are properly spaced and adapted 45 to engage corresponding recesses 12 in the clamp plates 4 so as to prevent creeping.

The clamps 4 are preferably made to rest against each other, as shown at 13 in Figure 2, and they rest firmly on top of the vertical flanges 6, as shown in this figure. These clamps are provided with laterally extending webs 14 to give the requisite stiffness to the structure.

The base 5 is made in one integral mass 55 and rigid so that the rail may have the requisite rigidity when in use. It will be noted

that the flanges 6 are parallel and spaced well apart from the vertical neutral axis of the rail so as to provide a very stiff rail which will resist all side thrusts due to the 60 conditions of service and the webs 7 and 14 on the base 5 and clamps 4, respectively, are placed away from the neutral axis so as to resist all bending of the rail when carrying a load.

Because of the disposition of metal, as herein set forth, my improved rail has more than ordinary rigidity so that the metal therein is more efficient than the metal in ordinary rails.

When laying the rail, care should be taken to see that the joints are broken as much as possible tween the treads 3, the clamps 4 and the bases 5. This tends to give a 70 smoothness of operation to all trains passing over the rail because of the extreme rigidity of the structure above set forth.

In view of the foregoing, the operation of my improved rail will be readily understood. It is installed and used much as ordinary 80 rails are installed and used with this exception. The assembly occurs on the job, the bases 5 being first secured in place and the tread 3 and clamps 4 are thereafter put in position and finally held by the bolts 8, as 85 above set forth. When any tread or treads 3 become worn out or undesirable for any reason, it or they may be readily removed and new ones substituted, as is obvious without disturbing any great length of rail and 90 the clamps 4 and bases 5 as well as the bolts 8 are permanent and may be used indefinitely.

While I have shown and described one embodiment of my invention, it is obvious 95 that it is not restricted thereto, but that it is broad enough to cover all structures that come within the scope of the annexed claims.

Having thus described my invention, what I claim is:

1. A rail with an integral base having upwardly extending, parallel flanges, clamps mounted on said flanges and a tread engaging said clamps, the tread, clamps and base being held in fixed relation by suitable securing means.

2. A railway rail composed of an integral base having upwardly extending flanges, clamps with parts resting on said base and provided with laterally extending flanges, a tread with means to prevent creeping held by said clamps and means for rigidly con-

necting the base, the clamps and the tread.

3. A rail composed of an integral base with upwardly extending flanges, clamping members resting on and against said flanges

5 and provided with laterally extending webs at their lower edges and tread receiving parts at their upper edges, a tread clamped

by said clamps and means for holding the same in rigid relation therewith and means for securing the tread, clamps and base 10 fixedly together.

In testimony whereof, I have hereunto set my hand this 5th day of November, 1927.

WALTER H. PFLUGER.
